United States Patent Office

Des. 186,241
Patented Sept. 29, 1959

186,241

DISHWASHING MACHINE

Carl Louis Otto, New York, N.Y., assignor to Aktiebolaget Electrolux, Stockholm, Sweden, a corporation of Sweden

Application July 28, 1958, Serial No. 51,945

Claims priority, application Sweden February 28, 1958

Term of patent 14 years

(Cl. D49—1)

FIG. 1

FIG. 2

FIG. 3

Fig. 1 is a perspective view of a dishwashing machine showing my design, the opposite side of the casing being plain except for the base as illustrated in Fig. 3;

Fig. 2 is a perspective view thereof with the closure member open; and

Fig. 3 is a fragmentary bottom perspective view thereof.

The dominant features of my design reside in the portions shown in full lines.

I claim:

The ornamental design for a dishwashing machine, as shown and described.
